UNITED STATES PATENT OFFICE.

EDMUND GOLLMER, OF NEW ULM, TEXAS.

ATTACHMENT FOR PHONOGRAPHIC REPRODUCERS.

1,219,934.

Specification of Letters Patent.

Patented Mar. 20, 1917.

Application filed June 30, 1915. Serial No. 37,301.

To all whom it may concern:

Be it known that I, EDMUND GOLLMER, a citizen of the United States, residing at New Ulm, in the county of Austin and State of Texas, have invented certain new and useful Improvements in Attachments for Phonographic Reproducers; and I do hereby declare the following to be a full, clear, and exact description of the invention, such as 10 will enable others skilled in the art to which it appertains to make and use the same.

This invention relates to new and useful improvements in attachments for phonographic reproducers and the principal object of the invention is to provide a damper adapted to be applied to reproducers to eliminate the crackling and grinding noises usually accompanying the use of such instruments.

20 Another object of the invention is to provide a device which will effectively bring out the tones accurately and clearly and which will eliminate other disturbing noises.

A further object of the invention is to 25 provide an attachment which may be made of cork, felt or other soft resilient material which will effectively take up the undesirable vibrations of the diaphragm.

With these and other objects in view, the 30 invention consists in the novel combination and arrangement of parts which will be fully set forth in the following specification and accompanying drawings, in which:—

Figure 1 is a side view in elevation of a 35 reproducer showing this improved device applied thereto.

Fig. 2 is a vertical sectional view through the reproducer on line 2—2 of Fig. 1 showing the diaphragm in elevation and also 40 showing the stylus bar in elevation, and

Fig. 3 is a perspective view of the attachment.

Referring now to the drawings by characters of reference, the numeral 1 designates 45 as an entirety the housing of the reproducer in which is mounted the diaphragm 2. The usual stylus bar 3 is secured to the diaphragm centrally in the ordinary manner and extends downwardly to the plate 4 mounted to rock on the bearing 5. The usual stylus retainer 6 is provided in which the needle or stylus 7 is secured by means of the thumb screw 8.

The attachment best illustrated in Fig. 3 50 is designated generally by the numeral 9 and this attachment 9 comprises a cylindrical

body 10 of a relatively soft resilient material such as rubber, cork, felt or the like, which is formed with the transversely extending groove 11 in which the stylus bar rests. 60

It will be apparent from the foregoing that in use the attachment is slipped beneath the stylus bar as illustrated in Figs. 1 and 2 and in this position it will be evident that the stylus bar will rest in the groove 11 hereinbefore referred to. The flat under face of the cylindrical body will engage the diaphragm 2 and serve to deaden the undesirable noises, thereby eliminating much of the crackling and grating sounds usually accompanying the use of talking machines and phonographs. 70

While in the foregoing there has been shown and described the preferred embodiment of this invention, it is to be understood 75 that such changes may be made in the combination and arrangement of parts as will fall within the spirit and scope of the appended claims.

What is claimed is:—

1. An attachment for reproducers comprising a cylindrical body of resilient soft material adapted to be positioned between the stylus arm and diaphragm to eliminate undesirable sounds. 80

2. In combination with a reproducer including a body and a diaphragm mounted within the body, and a stylus arm connected to the diaphragm, of a cylindrical pad of soft resilient material positioned beneath the 90 stylus arm and bearing on the diaphragm to eliminate undesirable sounds.

3. An attachment for reproducers including the combination with a reproducer having a stylus arm attached thereto, the said arm enlarging toward the end opposite that attached to the diaphragm, of a pad of a soft resilient material positioned between the stylus arm and diaphragm and arranged so that the same may be adjusted along the 95 stylus arm to vary the pressure on the diaphragm. 100

4. The combination with a reproducer having a diaphragm, a stylus arm attached centrally to the diaphragm, a needle holder at the end of the stylus arm opposite that which is connected to the diaphragm, the same arm being enlarged toward the needle holder, of a circular pad of a soft resilient material having a groove extending transversely through one face thereof, said pad being adapted to be positioned between the 110 115

stylus arm and the diaphragm with the stylus arm lying in the groove to prevent lateral movement of the pad with relation to the stylus arm.

- 5 5. The combination with a reproducer having a diaphragm, a stylus arm attached centrally to the diaphragm, a needle holder at the end of the stylus arm opposite that which is connected to the diaphragm, the
10 same arm being enlarged toward the needle holder, of a circular pad of a soft resilient material having a groove extending transversely through one face thereof, said pad

being adapted to be positioned between the stylus arm and the diaphragm with the stylus 15 arm lying in the groove to prevent lateral movement of the pad with relation to the stylus arm, said pad being adapted to be adjusted longitudinally of the stylus arm to vary its pressure against the diaphragm. 20

In testimony whereof I affix my signature in presence of two witnesses.

EDMUND GOLLMER.
